UNITED STATES PATENT OFFICE.

EDMUND T. PHELAN, OF CAMBRIDGE, MASSACHUSETTS.

BOOK-CUTTING MACHINE.

SPECIFICATION forming part of Letters Patent No. 350,318, dated October 5, 1886.

Application filed June 9, 1886. Serial No. 204,598. (No model.)

To all whom it may concern:

Be it known that I, EDMUND T. PHELAN, of Cambridge, in the county of Middlesex and State of Massachusetts, have invented a new 5 and useful Improvement in Book-Cutting Machines, of which the following is a specification.

This invention relates to the blocks of "all-round" book-cutting machines, and has for its 10 object to render such blocks expansible, so as to accommodate books of different sizes without building upon or otherwise altering or adding to the blocks.

In the accompanying drawings, in which 15 similar letters of reference indicate like parts, Figure 1 is a view in perspective of the block of a book-cutting machine embodying my invention. Fig. 2 is a vertical section taken on line *x*, Fig. 3. Fig. 3 is a vertical section 20 taken on line *y*, Fig. 2. Fig. 4 is a plan view of the under side of the expansive block.

A represents the bed of the machine, B the frame, and C the screw, all constructed substantially as usual.

25 D' is the central portion of the main portion D of the block—that is, that portion which is stationary horizontally—said block being raised and lowered in the ordinary manner by the screw C for pressing the books E upon the bed 30 A for the purpose of allowing their edges to be cut or trimmed by means of a knife, F, (see Fig. 2,) operated by a portion of the cutting-machine not shown in the drawings, but constructed in the ordinary manner.

35 H H are slides, triangular in shape, sliding by means of the dovetails H' in the dovetail grooves D" in the portion D of the block. These slides H are operated by the right-and-left screw I, which lies in the threaded up- 40 rights H", secured to said slides. The screw may be turned by means of the hand-wheels I' or by a socket-wrench applied to its end.

K K K are two pairs of slides, triangular in shape, sliding by means of the dovetails K' in the dovetail grooves D'" in the portion D of 45 the block. Each pair of these slides K is operated by a right-and-left screw, L, lying in the threaded uprights K", secured to said slides. The screws may be turned by means of the hand-wheels K'" or by a socket-wrench 50 applied to their ends.

The portion D of the block is chambered out at D"" in order to accommodate the screw I and its supports, and is slotted at D"" to accommodate the uprights K". When a book is 55 placed under the block to be cut or trimmed, the slides H are moved by means of the screw I to the point to which the front edges of the books are to be cut, and the slides K are moved by means of the screws L to the points to which 60 the upper and lower edges are to be cut, and the cutting-machine operated in the ordinary manner. Thus it will be seen that the portion D and the slides H K constitute an expansive block capable of holding and covering books 55 of various sizes for cutting.

Having thus fully described my invention, what I claim, and desire to secure by Letters Patent, is—

In a block for book-cutting machines, the 7c combination of the portion D, provided with the grooves D" D'" and chambers D""", the triangular slides H, provided with the dovetails H', uprights H", and right-and-left screw I, and the triangular slides K, provided with the 75 dovetails K', uprights K", and right-and-left screws L, substantially as and for the purpose described.

EDMUND T. PHELAN.

Witnesses:

HENRY W. WILLIAMS,
J. M. HARTNETT.
